US00D813445S

(12) **United States Design Patent** (10) **Patent No.:** **US D813,445 S**
(45) **Date of Patent:** **** Mar. 20, 2018**

(54) **E-CIGARETTE DEVICE**

(71) Applicant: **NERUDIA LTD.**, Liverpool (GB)

(72) Inventor: **Kenneth Scott**, Liverpool (GB)

(73) Assignee: **Nerudia Ltd.**, Liverpool (GB)

(**) Term: **15 Years**

(21) Appl. No.: **29/550,826**

(22) Filed: **Jan. 7, 2016**

(30) **Foreign Application Priority Data**

Jul. 7, 2015 (EM) 002732925-0001
Jul. 7, 2015 (EM) 002732925-0002

(57) **CLAIM**

The ornamental design for an e-cigarette device, as shown and described.

DESCRIPTION

FIG. 1 is a perspective view of the e-cigarette device.

FIG. 2 is a perspective view of the e-cigarette device.

FIG. 3 is a side view of the e-cigarette device.

FIG. 4 is a top view of the e-cigarette device.

FIG. 5 is a bottom view of the e-cigarette device.

FIG. 6 is a partial perspective view of the e-cigarette device showing a battery unit, shown removed for ease of illustration.

FIG. 7 is a partial perspective view of the e-cigarette device showing a battery unit.

FIG. 8 is a partial perspective view of the e-cigarette device showing a battery unit.

FIG. 9 is a top view of the battery unit of the e-cigarette device.

FIG. 10 is a bottom view of the battery unit of the e-cigarette device.

FIG. 11 is a partial perspective view of the e-cigarette device showing a cartomiser, shown removed for ease of illustration.

FIG. 12 is a partial perspective view of the e-cigarette device showing a cartomiser.

FIG. 13 is a partial perspective view of the e-cigarette device showing a cartomiser.

FIG. 14 is a top view of a cartomiser of the e-cigarette device; and,

FIG. 15 is a bottom view of a cartomiser of the e-cigarette device.

The broken lines depict portions of the e-cigarette device that form no part of the claim.

1 Claim, 10 Drawing Sheets
